UNITED STATES PATENT OFFICE.

ORIN N. BOYER, OF ONTARIO, OREGON.

CITRUS-FRUIT-SIZING MACHINE.

1,302,002.

Specification of Letters Patent. Patented Apr. 29, 1919.

Application filed May 28, 1918. Serial No. 237,104.

To all whom it may concern:

Be it known that I, ORIN N. BOYER, a citizen of the United States, residing at Ontario, in the county of Malheur and State of Oregon, have invented a new and useful Citrus-Fruit-Sizing Machine, of which the following is a specification.

My invention relates to a machine for properly sizing lemons and other citrus fruit, 10 difficult to size according to their diameter on account of their elongated shape; in which machine a system of concave shaped rollers, connected in pairs by eccentric, peculiarly shaped leverarms, travel by means of endless chains, running over sprocket wheels, 16 over differently inclined planes, gradually increasing the distance between the two rollers of each set.

The mechanism of my machine is illustrated in the accompanying drawing, in which—

Figure 1 is an elevation of the whole machine.

Fig. 2, a top view of the machine as it 23 appears, on the left of the line 1—2, with rollers and everything in place; on the right of the line 1—2, with rollers and leverarms removed.

Fig. 3, a vertical section of the machine on 30 the line 1—2.

Fig. 4, a plan and section, on line 3—4, of a couple of chain links, left and right, with attached lugs for carrying axles of rollers.

Similar letters refer to similar parts 35 throughout the several views.

The uprights or posts A, the longitudinal connections B, the cross-connections E, together with the pieces D, supporting the running planes for rollers and leverarms, constitute the frame work of the machine. The 40 posts support the axles *a* of the sprocket wheels *b*, which turn in metal bearings. The endless chains *e* are placed around these wheels, the openings of the links fitting over the sprockets of the wheels. At certain intervals links of the chains are provided with lugs *c*, with holes to carry the ends of the roller axles. The rollers *d* are made with a concave face, excepting a narrow strip at 45 each end, which is level to allow rolling. The rollers are arranged in pairs. The leading roller has its axle resting in the holes of the lugs *c* on the chain-links, in which it can rotate freely. The ends of the axle of the 50 second or following roller move freely in the

curved slots *f* of the lever-arms *o*, placed on each side of the roller, while the pivot end *g* of the leverarm is hung upon the axle of the leading roller, between roller and lug, allowing a free turning around the axle.

The rollers travel on the planes *h*, either inclined or horizontal, resting upon supports D. When the rollers are moving and the leverarms come into action, the weight of these arms is made such as to force the lower 65 curved face of the arms to continually touch the inclined plane *i* and thus compel a movement of the ends of the axle of the second roller in the curved slot *f* of the lever-arm, and thereby increase the distance between 70 leading and following roller.

When traveling from the feeding end *k* of the machine, the rollers ascend a slight incline: This is to gain sufficient height above the sorting table, which is at the feeding 75 end, to allow a removal of the sized fruit from underneath the rollers.

The lemons are automatically placed between the rollers at the feeding end *k*, from a chute from the sorting table.

This chute is adjusted to place a fruit in the pocket of each set of rollers. By traveling up the incline from the feeding end the lemons are in continual motion and rolling over, and by the time the leverarms reach 85 the downward plane and begin to act, the lemons are in the proper position to be sized accurately according to their diameter. After the leverarms begin to act, the space between the two rollers of each set is gradually increased, allowing each lemon at the proper time to drop through. Canvas compartments may be provided underneath for receiving the sized fruit, after dropping through between rollers.

At each end of the machine are two stop blocks *l*, to guide the rollers on their upward and downward travel and to prevent their dropping away from the machine.

A blocking wheel *m*, with projections *n* 100 on its face, at proper points, is placed between the sprocket wheels *b* at the feeding end of the machine, and fastened on the axle of the sprocket wheels, to fill the opening between two sets of rollers, when moving 105 around the sprocket-wheel at the feeding end, and to prevent fruit falling into this opening, when it is being fed to the machine.

The machine may be operated by hand by 110

means of a crank p , applied at the axle of the front wheels, or may be easily arranged for operation by a motor.

What I claim as my invention, and desire

5 to secure by Letters Patent, is:

1. A sizing machine comprising a frame, rotatable members mounted in said frame, endless members carried by the rotatable members and actuated thereby, a series of 10 rollers carried by said endless members in spaced relation to each other, pivoted levers carried by said endless members, said levers being provided with slots, a series of rollers having axles pivoted in the slots of said levers, tracks for said rollers and means engageable by the levers during the travel of the endless members for moving the slots along the last named roller axles, whereby said rollers will be moved away from the 15 first named rollers.
2. In a sizing machine, a frame, rotatable members mounted in said frame, endless members carried by the rotatable members, aligned bearings carried by the endless members, a roller journaled in said bearings, pivotally mounted arms carried by the endless members, members carried by said arms and provided with inclined slots, a second roller having its axle slidably mounted in 20 said slots, and means engageable by the last named members during the travel of the endless members for causing the slots of said slotted members to move along said axle and thereby separate the rollers.
3. In a sizing machine, a movable carrier, a roller mounted on said carrier, pivoted members movable with said carrier and provided with inclined slots, a second roller having an axle slidably mounted in said 25 slots, and means engageable by the slotted

members during the movement of said carrier for causing the slots of the slotted member to move along the axle of the second roller and thereby move the rollers apart.

4. In a sizing machine, a movable carrier, 45 a roller mounted on said carrier, pivoted arms movable with said carrier and provided with levers having inclined slots, a second roller having an axle mounted in said slots, and means engageable by the levers during 50 the travel of the carrier for rocking said arms on their pivots, whereby the axle of the second roller will move along the slots and cause the second roller to move away from the other roller.

5. In a sizing machine, a frame, pairs of sprocket wheels carried by the frame and spaced apart, endless sprocket chains engaging the sprocket wheels and carrying a series of pairs of spaced rollers, and a blocking 55 wheel rotating about an axis in alinement with the axes of one pair of sprocket wheels and having radially extending projections which enter spaces between pairs of said rollers and close the same.

6. In a sizing machine, a frame, pairs of sprocket wheels rotatably mounted in the frame on horizontal axes and spaced apart, endless sprocket chains engaging said wheels and provided with pairs of aligned spaced 60 bearing lugs, rollers having axles journaled in said lugs, arms pivotally mounted on the axles of the rollers, levers rigid with said arms and provided with inclined slots, other rollers having axles engaging said slots, and 65 means engageable by the levers during the travel of the sprocket chains for causing said arms to be rocked, whereby the axles of the second rollers will be moved along said slots.

ORIN N. BOYER
